UNITED STATES PATENT OFFICE.

JOHN S. GAJEWSKI, OF MILWAUKEE, WISCONSIN.

ANTISLIPPING ATTACHMENT.

940,799.

Specification of Letters Patent. Patented Nov. 23, 1909.

Application filed January 27, 1909. Serial No. 474,378.

To all whom it may concern:

Be it known that I, JOHN S. GAJEWSKI, a citizen of the United States, residing at Milwaukee, county of Milwaukee, and State 5 of Wisconsin, have invented new and useful Improvements in Antislipping Attachments, of which the following is a specification.

My invention relates to improvements in 10 anti-slipping attachments for boots and shoes.

The object of my invention is to provide a form of device which can be readily attached to, or removed from the foot, in substantially the same manner as a skate, or 15 which can be adjusted to any sized foot and used to prevent slipping when walking upon ice.

More particularly, the object of my invention is to provide a device of this kind which 20 will be sufficiently cheap and effective to create a demand for this class of articles.

I am aware of the fact that several attempts have been made to construct devices 25 of this kind, but in order to meet with popular favor, it is necessary that they shall not add materially to the weight and shall not be clumsy in appearance, nor of a character to interfere with the natural walking movements 30 of the wearer, and my improved device has been designed to meet these requirements.

In the following description, reference is 35 had to the accompanying drawings, in which—

Figure 1 is a side view of my invention; and Fig. 2 is a view of the same as seen from the underside.

Like parts are identified by the same reference characters in both views.

The device is principally constructed from sheet metal, a heel plate A and toe plate B being provided with over-lapping slotted members a and b respectively, the member b 45 being preferably arranged underneath the rear portion of the member a for a part of the distance and then passing through a transverse slot C to the upper surface of the heel plate A. These members a and b 50 are each provided with longitudinal slots d and d', the slots permitting a relative longitudinal movement of the heel and toe plates to correspond with the length of the 55 foot for which the device is to be adjusted. A leather heel clamp F and toe clamp G are

bound to the foot of the wearer by straps f and g. The under surfaces of the respective plates are provided with downwardly extending prongs H, H' and H".

In order that the device may be made of extremely light, thin material, the respective plates are reinforced on the under side by transverse bars J, the central portions of which are offset downwardly to receive the 60 members a and b respectively between the bars and the opposing members B and A, thus forming a truss to prevent the members from buckling. These bars are secured at their ends to the plates B and A by means of the prongs H', H" and H, such prongs being provided with annular flanges K and stems L, which pass through the ends of the bars J and the plates A or B and are riveted at L' to the upper surfaces of the plates. 65 The instep portion of the device is reinforced by a raised resilient plate M, which is secured to the respective plates A and B by means of the clamping bolt D' and by extending upwardly into the arch of the instep, prevents the plates from being buckled 70 upwardly at this point when the weight of the user is applied directly to an obstruction under the instep.

The prongs are preferably formed with a 75 view of guarding against slippage in any direction. The end prongs H are preferably tapered conically to a sharp point. The prongs H' and H" have wedge shaped extremities and may, if desired, be alike in construction, but should be turned at different angles, the wedge shaped edge of the prong H' extending transversely of the foot, while that of the prong H" extends longitudinally. If therefore the ice is slushy, the 80 prongs H' and H" will be relied upon to prevent slipping either laterally or longitudinally. On harder ice, the pointed prongs H will more readily enter the surface and 85 secure a firm grip.

Having thus described my invention, what I claim as new, and desire to secure by Letters Patent, is—

1. In a device of the described class, the combination of two longitudinal members, each composed of thin material with portions over-lapping, clamping members adjustably securing the other members together, reinforcing bars extending transversely across the under surfaces of said longitudinal members and having their ends secured to one of said longitudinal members 100

105

110

and their central portions offset sufficiently to receive a portion of the other longitudinal member, means for securing said longitudinal members to the foot of the wearer, and 5 downwardly projecting prongs connected with the respective adjustable members.

2. In a device of the described class, the combination of two longitudinal members, each composed of thin material with portions over-lapping, clamping members adjustably securing the other members together, reinforcing bars extending transversely across the under surfaces of said longitudinal members and having their ends 10 secured to one of said longitudinal members and their central portions offset sufficiently to receive a portion of the other longitudinal member, means for securing said longitudinal members to the foot of the wearer, and 15 downwardly projecting prongs connected with the respective adjustable members, said downwardly projecting prongs serving also to connect the reinforcing bars with such members.

25 3. In a device of the described class, the combination of two longitudinal members, each composed of thin material with portions over-lapping, clamping members adjustably securing the other members together, reinforcing bars extending transversely across the under surfaces of said longitudinal members and having their ends 20 secured to one of said longitudinal members and their central portions offset sufficiently to receive a portion of the other longitudinal member, means for securing said longitudinal members to the foot of the wearer, and 25 downwardly projecting prongs connected with the respective adjustable members, some of said prongs having pointed extremities and others having wedge shaped extremities.

30 4. In a device of the described class, the

combination of two longitudinal members, each composed of thin material with portions over-lapping, clamping members adjustably securing the other members together, reinforcing bars extending transversely across the under surfaces of said longitudinal members and having their ends 45 secured to one of said longitudinal members and their central portions offset sufficiently to receive a portion of the other longitudinal member, means for securing said longitudinal members to the foot of the wearer, and 50 downwardly projecting prongs connected with the respective adjustable members, together with an instep reinforcing member connected with one of said clamping bolts and extending upwardly in a position to fit the arch of a boot or shoe.

5. In a device of the described class, the combination of two longitudinal members, each composed of thin material with portions over-lapping, clamping members adjustably securing the other members together, reinforcing bars extending transversely across the under surfaces of said longitudinal members and having their ends 55 secured to one of said longitudinal members and their central portions offset sufficiently to receive a portion of the other longitudinal member, means for securing said longitudinal members to the foot of the wearer, and 60 downwardly projecting prongs connected with the respective adjustable members, some of said prongs having pointed extremities and others having wedge shaped extremities turned in opposite directions.

In testimony whereof I affix my signature 65 in the presence of two witnesses.

JOHN S. GAJEWSKI.
